UNITED STATES PATENT OFFICE.

FREDOLF PETERSON, OF SALEM, OHIO, ASSIGNOR TO THE AMERICAN CASE & REGISTER COMPANY, OF SALEM, OHIO, A CORPORATION OF OHIO.

FOLLOW-BLOCK FOR DOCUMENT-FILES.

1,050,166.

Specification of Letters Patent. Patented Jan. 14, 1913.

Application filed May 19, 1911. Serial No. 628,345.

To all whom it may concern:

Be it known that I, FREDOLF PETERSON, a subject of the King of Sweden, and resident of Salem, Columbiana county, Ohio, have 5 invented certain new and useful Improvements in Follow-Blocks for Document-Files, of which the following is a full, clear, and exact description.

My invention relates to that class of fol- 10 low blocks, specifically designed for use in document files wherein it is desired to hold the documents in compact form, but at the same time permit the documents to be released so that any particular document may 15 be withdrawn or moved for any purpose. The follower is formed of a length to correspond substantially with the width of the receptacle in which the documents are filed, one of the objects being to provide means to 20 hold the follower at any predetermined point within the limits of its movement and another object being whereby the follower block can be readily released and moved at pleasure.

25 The invention consists in certain features of novelty, by which the above objects are accomplished as hereinafter described.

In the drawings—Figure 1 is a detached perspective view of the follower block. Fig. 30 2 is a longitudinal section showing a portion of an ordinary document file and illustrating the follower block in position to properly 35 clamp and hold the documents in comparatively compact condition. Fig. 3 is a trans- 40 verse section of the document file showing the follower block in clamped or locked position.

Similar numerals of reference indicate corresponding parts in all the figures of the drawings.

45 In the accompanying drawing, 1 represents the follower block and 2 its supporting base or flange. The document receptacle 3 is of the ordinary construction and may be of any desired size, reference being had to 50 the kind of documents designed to be filed. The base 2 of the follower block is designed to rest upon the bottom of the receptacle 3 and for the purpose of allowing the follower block 1 to incline slightly forward or out of a true vertical position, said follower block is located at an acute angle to the base 2. One end of the follower block 1 is provided with the knobs 4, which are preferably formed of rubber or like material so as to

provide the proper adhesiveness to prevent 55 the follower block from slipping or sliding upon the inner vertical surface of the receptacle 3 against which the knobs are pressed, the opposite end of the follower block is provided with the cam 5 which is pivotally 60 attached to the back of the follower block 1 and is provided with the handle 6, which handle is set out or away from the back of the follower block so as to give proper clear- 65 ance and to bring the same into proper position to be easily actuated. When it is desired to lock or more specifically set the follower block at any desired point, the handle 6 is brought into a horizontal position or sub- 70 stantially so, at which time the cam 5 is brought into proper contact with the inner surface of the side of the receptacle oppo- 75 site from that upon which the knobs 4 are brought and by pressing the handle the cam will have a tendency to force the follower 80 block endwise, which endwise movement sets the knobs 4 in close contact with the inner surface of one of the vertical sides of the receptacle. When it is desired to release the follower block the handle 6 is moved upward, 85 thereby releasing the cam from against the inner face of the vertical side, at which time the follower block is free to be moved or slid at any desired point and again locked as above described by a downward movement 90 of the handle 6.

It will be understood that the cam should be pivotally connected to the follower block preferably by means of a screw 7 or its equivalent, said screw being so located that 95 the proper eccentric movement can be given to the cam 5.

Having fully described my invention what I claim as new and desire to secure by Letters Patent, is—

95 1. In a follower for document files the combination of a document receptacle, a document block provided with a base and the follower block inclined forward of a vertical line, said follower block provided 100 with frictional knobs at one of its ends, the opposite end thereof provided with a cam, said cam pivotally connected to the follower block and its contact edge adapted to be ex- 105 tended beyond the end of the follower block opposite that provided with the friction knobs, said cam provided with a handle, substantially as and for the purpose specified.

2. In a document file, the combination of a document receptacle, a follower provided with a supporting base, said follower provided with contact knobs upon one of its ends, said knobs adapted for contact with the adjacent side of the document receptacle, the opposite end of the follower provided with a cam, said cam adapted for contact with the opposite side of the document receptacle

and the handle connected to said cam, substantially as and for the purpose specified.

In testimony that I claim the above, I have hereunto subscribed my name in the presence of two witnesses.

FREDOLF PETERSON.
